UNITED STATES PATENT OFFICE.

HOWARD EARL HOOVER, OF CHICAGO, ILLINOIS, ASSIGNOR TO HOOVER SUCTION SWEEPER COMPANY, OF NEW BERLIN, OHIO, A CORPORATION OF OHIO.

CLEANER.

1,329,048.

Specification of Letters Patent. Patented Jan. 27, 1920.

Application filed June 2, 1916. Serial No. 101,235.

To all whom it may concern:

Be it known that I, HOWARD EARL HOOVER, a citizen of the United States, residing at Chicago, in the county of Cook and State of

5 Illinois, have invented a certain new and useful Improvement in Cleaners, of which the following is a specification.

My invention relates to handle supporting devices such as may be used in connection 10 with suction sweepers and the like. It has for one object to provide a new and improved form of handle control whereby the suction sweeper or the like may be moved or manipulated and carried with the minimum of difficulty by the operator. Another object is to provide means for limiting or 15 controlling the movement of the handle with respect to the case. Another object of my device is to provide stopping means for 20 rigidly controlling the position of the handle. Other objects of my invention will appear from time to time in the specification.

My invention is illustrated more or less diagrammatically in the accompanying 25 drawings wherein—

Figure 1 is a side view of a suction sweeper showing my handle in position;

Fig. 2 is a detailed section on an enlarged scale along the line 2—2 of Fig. 1;

30 Fig. 3 is a detail of the spring clip on the handle;

Fig. 4 is a detail on an enlarged scale of a side elevation showing my handle supporting and holding device;

35 Fig. 5 is a modified form shown in side elevation as applied to a suction cleaner.

Fig. 6 is an enlarged side elevation of my hook device.

Like parts are indicated by like characters 40 in all of the figures.

A is a suction cleaner. It is mounted on rollers A¹, has a motor housing A², a fan housing A³ and a bag A⁴. A⁵ is a suction hood. The operation of the cleaner is well known and the rotation of the motor drives 45 the fan which sucks air and dirt in through the hood, through the fan, and discharges it into the bag.

B is a cleaner handle. It supports, adjacent its upper end, a spring B¹ which

holds and supports the bag. B² B² are clips about which the electric wire of conduits B³ may be wound. This conduit is provided with a plug B⁴ for making connection with a suitable source of electric power and 55 passes down to a suitable switch on the motor housing whereby it may be controlled.

The handle stopping device of all the figures except Fig. 6 is one form I have used which has advantages, although it is more 60 complicated than the device shown in Fig. 6. C is a clip on one end of the handle bail on the arm C¹ and secured by the screw C². The clip is provided with an upwardly bent lug C³ and a perforation C⁴. C⁵ is a 65 stop on the side wall of the fan housing. One side C⁶ of the stop is at right angles to the plane of the spring clip, the other side C⁷ is curved as indicated in Fig. 2. A movement of the handle bail in one direction will 70 cause the clip to ride up over the side and in the other will cause the stop to engage the aperture in the clip and thus bring the handle to rest. In the modification and the simplest and perhaps preferred form of this 75 device I have substituted for the stop C⁵ a device I have substituted for the stop C⁵ a screw C⁸ and for the lug C³ and its perforated end the hook C⁹. The engagement of the hook and stop will arrest movement of the handle in one direction but permit it to 80 move in the other.

D is a stop lug projecting downwardly from the central rear portion of the handle bail. It is adapted to engage a stop bar D¹. This stop bar is pivoted on lugs D², is 85 curved as shown substantially concentric with the path of the stop lug D as the handle bail rotates and is provided with a recess or depressed portion D³, terminating in hooks D⁴ D⁵, adapted to engage one or the 90 other side of the stop D as the case may be. D⁶ is a spring adapted to engage the under side of the stop bar D¹, and provided with a hook end D⁷ to overhang a lug D⁸ on the under side of the bar. When the bar is 95 pressed into the position shown in full lines on Fig. 1, this hook engages the upper side of this lug, and holds the bar down. If the bar is lifted up until the spring disengages from its hooking position with re- 100

spect to the lug, the spring will then engage the end of the lug and tend to hold the bar yieldingly out so that it will come into engagement with the stop member D, and under ordinary circumstances the stop lug D will slide upon the upper surface of the depression D³, being limited in its movement by contact with the hooks D⁴, D⁵. When the operator wishes to move the handle into the position shown in dotted lines on Fig. 1, he depresses the bar against the spring to permit the lug D to pass over the hook D⁵ without engaging it. He may or may not cause the parts to assume the position shown in full lines in Fig. 1, but in any event this would permit him to drop the handle and handle bail down into the prone position shown in dotted lines in Fig. 1.

It will be evident that while I have shown in my drawings an operative device, still many changes might be made both in size, shape and arrangement of parts without departing materially from the spirit of my invention, and I wish therefore that my drawings be regarded as in a sense diagrammatic.

In the modified form as shown the handle bail D⁸ is pivoted on one arm thereof at a point intermediate the handle and the end of the bail with a curved stop bar E. This curved stop bar E has a recessed lower side as at E¹ the recess being bounded by the hooks E², E³. This recessed portion is adapted to ride or slide along the lug or stop E⁴ projecting outwardly from the flange E⁵ as indicated. This bar is held in engagement with the stop by gravity. When the operator wishes to free it, all he has to do is to lift it up against gravity. When it is out of engagement with the stop E⁴ its downward rotational movement is limited by a stop E⁶ on the handle bail, the relation of the parts is such that with the curved bar resting upon the stop, it is at a point such that as the handle rotates in a clockwise direction, the curved tip on the end of the stop bar will ride over the stop E⁴ and bring the parts into the operative position as shown in Fig. 5.

In the form of my device shown in detail and enlarged in Fig. 6 I rely upon the weight of gravity to hold the handle in the upright position. It will be observed that it is in the upright position when the parts are in the position shown in full lines. The bail D⁸ extends to the left, and the weight of the handle is all applied along a line at the left of the center of rotation of the handle bail. The hook C⁹ which is concentric with the center of rotation of the bail is anchored by means of the tail C¹. It has a curved hook portion adapted to engage the stop C⁸, which stop takes the form of a stud screw-threaded into the wall of the vacuum cleaner casing. When it is desired to put the device into operation, the parts are ro-

tated into the position shown in dotted lines, and the machine is operated or manipulated by the handle in the usual manner. When it is to be stored, the parts are rotated into the position shown in full lines and gravity holds the handle in the position with the hook bearing against the stop and nothing further is required.

The use and operation of my invention are as follows:

The handle is pivoted to the case and adapted to move downwardly to the position shown in dotted lines in Fig. 4 where it rests upon a projection on the case. In this position the device is adapted to be manipulated by the handle so that it can pass under low objects such as beds and pieces of furniture.

The handle may also be tilted in the opposite direction as indicated in dotted lines in Fig. 1 and finally in the full lines of Fig. 1. In this position it is held by the engagement of the pin with the screw and this is the position for storage or the out-of-use position. Intermediate these two positions it is desirable to have means whereby when desired the handle can be locked or connected with the case so that the case may be tilted by means of the handle and this is effected by the double stop structure, which when in active position as shown in Fig. 4 stops the handle from movement in either direction as desired and at some point intermediate the two extreme positions first above referred to. By pushing down on the handle when it is in the position shown in full lines in Fig. 4 the front end of the sweeper may be lifted to permit it to be pushed forward over objects which otherwise might interfere with its action or for the purpose of going easily over any obstruction which the machine might encounter.

When the handle is brought to the position shown in dotted lines in Fig. 4 and then pressure applied to lift up on the handle the rear end of the machine is raised for the purpose of facilitating the movement of the machine over the floor.

By these devices therefore we have means whereby the handle is brought to rest in its lowest position and also in its upright position and means whereby when desired it can be restricted to a limited movement intermediate these two positions and when at the ends of such limited movement in either direction the handle if still further pressed will tend to tilt the machine in the desired direction. The ordinary movement of the handle while the machine is in ordinary use is approximately between the two last named stops so that normally the intermediate stop device would be in operative position. The intermediate stop serves the further purpose of thus holding the handle at approximately the working position when it is momentarily released for the manipulation of furniture.

or other purposes. In the two forms of the intermediate stop device the result is of course substantially the same. Broadly speaking, the pivoted arm is in one case attached to the sweeper proper and in the other to the handle.

I claim:

1. The combination with a handle bail and a case to which it is pivoted of a movable handle stop comprising a movable member adapted when in one position to confine the pivotal movement of the handle between predetermined limits and when in another position to leave the handle free to swing on its pivot and means for holding such stop in either of said positions.

2. The combination with a handle bail and a case to which it is pivoted of a movable handle stop comprising a movable member adapted when in one position to confine the pivotal movement of the handle between predetermined limits and when in another position to leave the handle free to swing on its pivot and yielding means for holding such stop in either of said positions.

3. The combination with a handle bail and a case to which it is pivoted of an adjustable stop member provided with two stops pivotally secured to the case and adapted to engage the handle and means for holding such stop member in or out of engagement with the handle.

4. The combination with a handle bail and a case to which it is pivoted of an adjustable stop member provided with two stops pivotally secured to the case and adapted to engage the handle and means for yieldingly holding such stop member in or out of engagement with the handle.

5. The combination with a handle bail and a case to which it is pivoted of a projection on the bail, a stop member provided with two stops and adapted to engage such projection, said stop member pivoted to the case and means for holding it in or out of engagement with the handle.

6. The combination with a handle bail and a case to which it is pivoted of a projection on the bail, a stop member provided with two stops and adapted to engage such projection, said stop member pivoted to the case and means for yieldingly holding it in or out of engagement with the handle.

7. The combination with a handle bail and a case to which it is pivoted of a projection on the bail, an arc-shaped stop member provided with two stops and adapted to engage such projection, said stop member pivoted to the case and means for holding it in or out of engagement with the handle.

8. The combination with a handle bail and a case to which it is pivoted of a pro-

jection on the bail, an arc-shaped stop member provided with two stops and adapted to engage such projection, said stop member pivoted to the case, and yielding means for holding it out of engagement with the projection and for thrusting it into engagement with the projection.

9. The combination with a handle bail and a case to which it is pivoted of a projection on the central portion of the bail, an arcuate stop member adjacent the path of such projection, yielding means for holding such member in position, said member being pivoted adjacent such means, a stop hook on said member adapted to engage the projection on the handle bail.

10. The combination with a handle bail and a case to which it is pivoted of a pivoted arcuate stop member, and yielding means for holding such stop member in or out of the path of the handle bail.

11. The combination with a handle bail and a case to which it is pivoted of a pivoted arcuate stop member, and yielding means for holding such stop member in and out of the path of the handle bail, such yielding means comprising a spring hook, a lug on the stop member adapted to engage the hook either at its end to hold the stop member in the operative position or on its side to hold the stop member in the inoperative position.

12. The combination with a handle bail and a case to which it is pivoted of an arcuate pivoted spring held stop member, the upper bail engaging portion of such member being recessed, the bottom of the recess being substantially concentric with the path of the bail, such recess terminating in hooks oppositely disposed and adapted to engage opposed sides of the handle bail.

13. The combination with a handle bail and a case to which it is pivoted of an arcuate pivoted spring held stop member, the upper bail engaging portion of such member being recessed, the bottom of the recess being substantially concentric with the path of the bail, such recess terminating in hooks oppositely disposed and adapted to engage opposed sides of the handle bail, a lug projecting downwardly from the stop member adapted to engage the holding spring, said spring being arranged to engage either the side or the end of the lug to yieldingly hold the stop member in operative or inoperative position.

14. The combination with a handle bail and a case to which it is pivoted of a lug projecting inwardly from the central portion thereof having two downwardly and outwardly inclined opposed surfaces, a stop member having opposed hooks adapted to engage one or other of the opposed surfaces.

on the lug and yielding means for holding such member into engagement with the lug.

15. The combination with a handle bail and a case to which it is pivoted of a stop on one and a curved bar with motion limiting means pivoted on the other in engagement with the stop, one side of said stop bar being provided with a recessed portion adapted to engage the stop, said recessed

portion terminating at either end in stop en- 10
gaging hooks.

In testimony whereof I affix my signature, in the presence of two witnesses, this 26th day of May, 1916.

H. EARL HOOVER.
